UNITED STATES PATENT OFFICE.

ROSE L. OPPER AND JOHN M. OPPER, OF OMAHA, NEBRASKA.

ELECTRICAL HAIR WAVING AND CURLING DEVICE.

Application filed September 20, 1926. Serial No. 136,469.

This invention relates to a device for waving or curling hair, and has for its object, broadly, to provide electrically heated holders upon which the hair of the individual 5 may be wound, supported or held to cause waving, flat-waving or curling, said holders to be of such form that they will be convenient in use and will heat the hair uniformly and without injury. The invention 10 includes a plurality of holders so arranged that they may be operated under control of an individual for self-treatment of his or her own hair or may be used by hair dressers generally, means being provided for heating the hair uniformly as to degree of heat and duration of exposure to heat.

With these objects in view and others to be mentioned hereinafter the invention presents a novel and useful construction, combination and arrangement of parts as described herein and claimed and as illustrated in the accompanying drawing, it being understood that changes may be made in form, size, proportions and minor details without departing from the spirit of the invention, said changes being determined by the scope of the invention as claimed.

In the drawing, Fig. 1 is an end view of the holder. Fig. 2 is a view of the same showing parts thereof in longitudinal section. Fig. 3 is a side view of the holder. Fig. 4 is a side view of the clamp and Fig. 5 is a plan view of the same. Fig. 6 is a diagrammatic view illustrating the use of a main electrical conductor in communication with a plurality of flexible electrical conductors having plugs for mountings in the several holders.

Referring now to the drawing for a more particular description, we provide a plurality of holders 6 for supporting the hair to be treated, each holder consisting, in part, of an elongated casing 7 preferably constructed of metal so that it will not become injured by action of heat, but will operate as a good conductor of heat. While these holders have been shown in the drawings to have a greater width than thickness, they may be circular or elliptical in cross-section.

However, for producing wavy forms and effects, it is preferred that the width of a casing shall be greater than its thickness and that a pair of opposed grooves or lon-

gitudinal depressions 8 be employed at the medial line of the casing. 55

At 9 is indicated an electrical insulating member disposed at the inner side of the casing. This insulating element may consist of a small sheet of mica or other material which will operate as a good conductor 60 of heat and as a non-conductor of electricity.

At 10 is indicated a supporting-core for an electrode 11, said core being constructed of vulcanized rubber or other electrical insulating material and provided longitudinally with an aperture 12 for receiving the rectilinear part α of the electrode. Also the core is provided in one of its ends with an aperture 13 for receiving an end-portion of the electrode and an aperture 13' at its opposite end to provide a mounting for the clamp 14. 70

The insulating core 10 is also provided to open on one of its ends with a pair of metallic sleeves 16 to operate as sockets in electrical communication with the ends of the coiled part of the electrode and the rectilinear part α thereof. 75

As thus described the parts may be conveniently manufactured, and may be readily assembled. After the electrical insulating jacket 9 has been inserted in the casing the core 10 with its electrode 11 may then be inserted within the jacket, all parts of the electrode and said sleeves being completely 85 insulated, electrically, and the jacket 9 and core 10 may be secured to the inner wall of the casing by any suitable means, plugs 17 of electrical insulating material, such as vulcanized rubber, being shown for this purpose. 90

The clamping-bar 14 is of loop-form and is arranged to swing from one of the ends of the casing, said bar or loop engaging in the aperture 13' of the core 10, as best shown 95 in Fig. 2 of the drawings, and in operation the clamp or loop may be swung outwardly to permit the hair to engage the casing, and when the bar is swung inwardly the hair will be pressed against the opposed sides and into the grooves of the casing, the free end of the clamp being then caught in the notch 18 which is provided for receiving the end of the clamp. Since the clamp is constructed of elastic material it may be manually controlled, and after said clamp or loop 100 105

has been swung into locked relation with the casing it will remain and will press the hair against the sides of the casing but may be manually released from the notch 18 5 when desired.

It will be understood that any suitable number of holders may be used for waving or curling the hair of an individual and each holder may be electrically heated. Numeral 19 indicates a main electrical conductor in an electrical circuit said conductor 10 19 being in electrical communication, subject to the control of an electrical switch 20, with a plurality of flexible electrical conductors 21, each of the last named conductors being provided with a plug or pair 15 of prongs 22 for engaging in the sockets of a holder; and an operator, after the holders have been placed in position for treatment 20 of the hair to produce waving or curling, may then place the plugs or prongs in the sockets of the cores of the several holders, and on account of electrical action the casings and hair thereon will become heated. 25 The switch 20 may then be used for terminating the electrical current to said holders, and the plugs 22 may be removed from the sockets, and after the holders have become cooled they may be removed from the 30 hair.

Numeral 23 indicates a covering or jacket with which the resilient clamp or loop may be inserted, if desired, to prevent injury to the scalp, it being understood that the 35 growth of hair may be abundant in some instances and may be scanty in other instances, and the jacket for the clamp may be used if needed. The jacket 23 is preferably constructed of rubber, but any other flexible material may be used, operating as a 40 non-conductor of heat.

It will be noted that the curved parts of

the electrode are disposed closely adjacent to the casing, and therefore the holders will become quickly heated after the electric 45 switch 20 has been moved.

Among some of the benefits to be derived by use of the invention, it may be stated that by the means described the degree of heat will be practically uniform for the several holders, this being accomplished by subjecting the holders to heat during a specific period of time, each holder also being subjected to the same degree of heat, thereby avoiding injury to the hair and producing 55 uniform waving or curling. The holders are of such construction that they will be convenient in use; and since the parts are few they may be manufactured economically. 60

We claim as our invention,—

1. A hair waving and curling device comprising a metallic casing for supporting the hair provided with grooves in its opposed sides, an electric heating element disposed in said casing, and a clamp of loop form mounted to swing from the casing for pressing the hair into said grooves of the casing. 65

2. A hair waving and curling device 70 comprising a casing having grooves in its opposed sides, an electric heating element in said casing, and a substantially U-shaped clamping member pivoted on said casing and having its side portions adapted to rest 75 in the closed position opposite to said grooves whereby to force the hair into the grooves, said casing and clamping member having an interlocking means for holding the clamping member in the closed position. 80

In testimony whereof, we have affixed our signatures.

ROSE L. OPPER.
JOHN M. OPPER.
